(57) **ABSTRACT**

A coaxial connector having locking projections is provided
which can be press-fittingly attached to and detached from a
groove of a receptacle plural times with a smaller load and has
a longer life without increasing the height of the coaxial
connector. A tubular portion of a housing is rounded and has
a gap formed by opposite ends of the tubular portion. A first
locking projection is formed at a position diametrically oppo-
site to the gap and a second locking projection and a third
locking projection are located at positions that are spaced
away from the first locking projection by about 90° or more in
a circumferential direction. A circumferential length of each
projection is set to be smaller than a circumferential length of
an interval between the first locking projection and the second
or third locking projection.

FIG. 12 PRIOR ART# 1 COAXIAL CONNECTOR

BACKGROUND OF THE INVENTION

1. Field of the Invention

The present invention relates to a coaxial connector for connecting a coaxial cable to a receptacle.

2. Description of the Related Art

The use of very small and thin communication equipment has recently become more prevalent. Correspondingly, electronic components used in such equipment have very small sizes and low heights. Coaxial connectors are also required to have smaller sizes and lower heights. Known coaxial connectors of this type are described in, e.g., Japanese Unexamined Patent Application Publication No. 2005-50720 and International Application WO2006/087953.

The coaxial connector described in Japanese Unexamined Patent Application Publication No. 2005-50720 includes, as illustrated in FIG. 11, a housing 130 connected to an outer conductor 101 of a coaxial cable 100 and having a tubular portion 131 which is capable of being press-fitted and locked into a groove 122 formed in an outer conductor 121 of a receptacle 120, a socket 135 connected to a center conductor 102 of the coaxial cable 100 and connected to a center conductor 123 of the receptacle 120, and an insulating bushing 136 fitted over the tubular portion 131 of the housing 130 and holding the socket 135.

In the coaxial connector of FIG. 11, as schematically illustrated in FIG. 12, the tubular portion 131 of the housing 130 has a substantially C-shape with a gap 131a left at one side and has a lock portion 132 formed along an entire circumference of the tubular portion 131 so as to project into the groove 122 which is formed in the outer conductor 121 of the receptacle 120. When the tubular portion 131 is attached to and detached from the outer conductor 121, the lock portion 132 constitutes a cantilevered beam while a portion C diametrically opposite to the gap 131a serves as a fulcrum. Therefore, any point of the beam over an entire beam length L acts as a point of effort (as indicated by hatching).

Considering the cantilevered beam from the viewpoint of dynamics, a larger force is required to generate a certain displacement of the beam as the point of effort approaches the fulcrum C. Accordingly, a load required to press-fit the tubular portion 131 at a point near the fulcrum C is increased to such an extent that the load tends to exceed a spring elastic limit displacement. This may result in a risk that the lock portion 132 and/or the groove 122 is plastically deformed and the coaxial connector can no longer be used even after attaching and detaching the coaxial connector once. In particular, because the height of the tubular portion 131 is reduced due to the above-described recent tendency toward the lower height of the coaxial connector, it is more difficult to ensure sufficient spring elasticity of the tubular portion 131.

SUMMARY OF THE INVENTION

Preferred embodiments of the present invention provide a coaxial connector which can be attached to and detached from a receptacle many times with a smaller load and has a longer life, without increasing the height of the coaxial connector.

According to a preferred embodiment of the present invention, a coaxial connector for connecting a coaxial cable having a center conductor and an outer conductor to a receptacle having a center conductor and an outer conductor, the coaxial connector including a housing connected to the outer conductor of the coaxial cable and having a tubular portion arranged

2

to be press-fitted and locked into a groove provided in the outer conductor of the receptacle, a socket connected to the center conductor of the coaxial cable and arranged to be connected to the center conductor of the receptacle, and an insulating bushing mounted into the tubular portion of the housing and holding the socket, wherein the tubular portion has a substantially C-shape extending perpendicularly or substantially perpendicularly to a direction in which the tubular portion is press-fitted to the outer conductor of the receptacle, and has a gap extending parallel or substantially parallel to the press-fitting direction, and the tubular portion has three first, second and third locking projections to be press-fitted and locked into the groove provided in the outer conductor of the receptacle to extend perpendicularly or substantially perpendicularly to the press-fitting direction, the first locking projection being located at a position on a circumference of the tubular portion diametrically opposite to the gap, the second locking projection and the third locking projection being located at positions that are spaced away from the first locking projection by about 90° or more in a circumferential direction, and a circumferential length of each of the first, second and third locking projections is smaller than a circumferential interval between the first locking projection and the second or third locking projection.

In the coaxial connector, when the tubular portion of the housing is locked to the outer conductor of the receptacle, the first locking projection is arranged to act as a fulcrum and each of the second and third locking projections having a predetermined beam length with respect to the fulcrum are arranged to act as a point of effort instead of the entire circumference of the tubular portion being press-fitted into the groove of the receptacle. Such an arrangement eliminates the necessity of applying a strong load. As a result, the locking projections of the tubular portion are prevented from displacing beyond the spring elastic limit displacement when the coaxial connector is attached and detached. Further, the coaxial connector can be attached and detached many times without problems.

According to a preferred embodiment of the present invention, the coaxial connector can be attached to and detached from the receptacle without requiring such a large load, and can sufficiently endure a very large number of attaching and detaching operations. Further, since the tubular portion of the housing is not required to have a large size in the press-fitting direction, the demand for a lower height of the coaxial connector is not impeded.

Other features, elements, steps, characteristics and advantages of the present invention will become more apparent from the following detailed description of preferred embodiments of the present invention with reference to the attached drawings.

BRIEF DESCRIPTION OF THE DRAWINGS

FIG. 1 is an exploded perspective view of a coaxial connector according to a preferred embodiment of the present invention.

FIG. 2 is a developed view of a tubular portion of a housing.

FIG. 3 is a perspective view illustrating assembly procedures of the coaxial connector illustrated in FIG. 1.

FIG. 4 is a sectional view of the coaxial connector taken along the longitudinal direction, the view illustrating the state where the coaxial connector is fitted to a receptacle.

FIG. 5 is a sectional view of the coaxial connector taken along the transverse direction, the view illustrating the state where the coaxial connector is fitted to the receptacle.

FIG. 6 is a perspective view of the housing when viewed from below.

FIG. 7A is a side view of the coaxial connector, and FIG. 7B is a bottom view of the coaxial connector.

FIG. 8A is a sectional view illustrating the state where a projection on the tubular portion of the housing is locked into a groove provided in an outer conductor of the receptacle, and FIG. 8B is a sectional view illustrating the relationship between a region of the tubular portion other than the projection and the groove.

FIG. 9 is a perspective view illustrating a modification of the tubular portion of the housing.

FIG. 10 is a developed view of the tubular portion according to the modification.

FIG. 11 is a sectional view of a known coaxial connector.

FIG. 12 is an explanatory view illustrating the state where a tubular portion of the known coaxial connector operates as a cantilevered beam.

DETAILED DESCRIPTION OF THE PREFERRED EMBODIMENTS

A coaxial connector according to preferred embodiments of the present invention will be described below with reference to the accompanying drawings.

A coaxial connector 1 is adapted for electrically connecting a coaxial cable 50 to a receptacle 41. As illustrated in FIG. 1, the coaxial connector 1 includes a housing 21 made of a metallic material having spring elasticity, a bushing 22 mounted into the housing 21 and made of an insulating resin material, a socket 2 held in the bushing 22 and made of a metallic material having spring elasticity, and an insulating sheet 20.

The housing 21 includes a tubular portion 24 arranged to be press-fitted and locked to an outer conductor 42 of the receptacle 41, a lid portion 26 covering an upper opening of the tubular portion 24, a pair of cover portions 27 each having a circular-arc shape and extending from the tubular portion 24 so as to cover an outer conductor 51a of the coaxial cable 50 from both sides, and a crimped portion 28 extending from the lid portion 26 and capable of being crimped to fit over the pair of cover portions 27, thus grasping the coaxial cable 50 from above the cover portions 27. A portion of the crimped portion 28 serves as a claw portion 28a that is to be crimped to fit over an outer skin 51b of the coaxial cable 50. The bushing 22 is inserted into the tubular portion 24 of the housing 21 through the upper opening of the tubular portion 24 and is fixedly held therein.

Further, the tubular portion 24 of the housing 21 has a gap 29 and locking projections 25a, 25b and 25c, which will be described in detail later.

The bushing 22 has a tapered shape such that an outer diameter at a fore end thereof as viewed in the direction of insertion into the tubular portion 24 of the housing 21 (i.e., an outer diameter of a lower portion) is smaller than that of an upper portion. Two lugs 22a are projected from the upper portion of the bushing 22 in the radial direction opposite to each other. Those two lugs 22a are fitted to cutouts 24a formed in the tubular portion 24 at the upper opening side thereof. With that arrangement, the bushing 22 is properly positioned with respect to the housing 21.

Further, the bushing 22 preferably has a rectangular or substantially rectangular fitting recess 32 into which a support portion 3a of a spring or elastic contact portion 3 of the socket 2 is fitted, and an elastic-contact-portion accepting hole 35 penetrating the bushing 22 in the axial direction and accepting the elastic contact portion 3 of the socket 2. The

elastic-contact-portion accepting hole 35 has a space sufficient to accept the elastic contact portion 3 of the socket 2 even in the state where the elastic contact portion 3 is displaced outward in the radial direction upon press-fitting of a center conductor 43 of the receptacle 41 to the elastic contact portion 3.

The socket 2 includes the elastic contact portion 3 and a connecting portion 9 that is to be connected to a center conductor 51c of the coaxial cable 50. The elastic contact portion 3 is formed preferably by rounding a leaf spring (made of phosphor bronze), which has a constant width and a thickness of about 0.1 mm, into a substantially C-shaped cross-section. Upon the press-fitting of the center conductor 43 of the receptacle 41, the elastic contact portion 3 of the socket 2 is displaced outward in the radial direction while holding pressure contact with an outer peripheral surface of the center conductor 43 at predetermined locations. An inner diameter of the elastic contact portion 3 preferably is set to be smaller than an outer diameter of the central conductor 43 within the range not exceeding a spring elastic limit. A lower end 3b of the elastic contact portion 3 is chamfered such that the central conductor 43 can be easily inserted.

The elastic contact portion 3 has the support portion 3a on the upper side thereof. The support portion 3a preferably has substantially the same size as that of the fitting recess 32 of the bushing 22 and is integrally extended from the elastic contact portion 3. The connecting portion 9 for electrical connection with the central conductor 51c of the coaxial cable is integrally extended from the support portion 3a. The connecting portion 9 is folded to extend perpendicularly or substantially perpendicularly to the axial direction of the elastic contact portion 3.

As illustrated in FIG. 3, the socket 2 is assembled with the bushing 22 such that the support portion 3a of the elastic contact portion 3 is fitted into the fitting recess 32 of the bushing 22 and the elastic contact portion 3 is accepted in the elastic-contact-portion accepting hole 35. Then, the bushing 22 is accepted in the tubular portion 24 of the housing 21. A fore end portion of the central conductor 51c of the coaxial cable 50, which has been machined to be adapted for termination, is arranged on the connecting portion 9 of the socket 2, and the central conductor 51c and the connecting portion 9 are soldered together. As a result, the socket 2 is electrically connected to the central conductor 51c of the coaxial cable 50.

The insulating sheet 20 having been cut into a predetermined shape is arranged in a recess 22b formed in an upper surface of the bushing 22. In that state, the lid portion 26 of the housing 21 is folded so as to cover the upper surface of the bushing 22.

Thus, as illustrated in FIGS. 4 and 5, the insulating sheet 20 insulates the cover portion 26 of the housing 21 from a connecting section in which the socket 2 and the central conductor 51c of the coaxial cable 50 are connected to each other. Because the insulating sheet 20 can be formed of a thin sheet, the presence of the insulating sheet 20 does not impede a reduction in the height of the coaxial connector 1. As an alternative, in assembly, the insulating sheet 20 may be previously pasted to the backside of the cover portion 26 of the housing 21 (as indicated by a dotted line in FIG. 3).

Next, the crimped portion 28 of the housing 21 is crimped to fit over the pair of cover portions 27, thus grasping the coaxial cable 50 from above the cover portions 27. Further, the claw portion 28a is crimped to fit over the outer skin 51b of the coaxial cable 50.

FIG. 6 is a perspective view of the housing when viewed from below, and FIG. 2 is a developed view of the tubular

portion 24. Note that the cover portion 26 and the crimped portion 28 are omitted in FIG. 2 for simplification of the drawing.

The tubular portion 24 is preferably shaped, illustrated in FIG. 6, by rounding the tubular portion 24 in the developed form, illustrated in FIG. 2, into a substantially C-shape and by folding the cover portions 27 along dotted lines B. With the tubular portion 24 rounded into the substantially C-shape, opposite ends D of the tubular portion 24 are positioned close to each other such that the gap 29 is formed to extend parallel to a press-fitting direction A (see FIG. 6).

A lower inner peripheral portion of the tubular portion 24 is locked into a groove 42a (see FIG. 5), which is formed in an outer peripheral portion of the outer conductor 42 of the receptacle 41, upon press-fitting of the coaxial connector 1 into the receptacle 41 in the direction of arrow A. To realize the locking, first, second and third locking projections 25a, 25b and 25c are formed in a lower inner peripheral surface of the tubular portion 24 by pressing such that those projections slightly project inward of the tubular portion 24. As illustrated in FIG. 7B, the first locking projection 25a is located at a position on the circumference of the tubular portion 24 diametrically opposite to the gap 29, and the second and third locking projections 25b and 25c are located at positions that are spaced away from the first locking projection 25a by about 90° or more in the circumferential direction. A circumferential length L11 of each of the projections 25a, 25b and 25c preferably is set to be smaller than a circumferential interval L12 between the projections. The circumferential length L11 of each projection is preferably about 1/5 or less, for example, of the entire circumference of the tubular portion 24.

Stated another way, when the housing 21 is fitted to the receptacle 41, the projections 25a, 25b and 25c of the tubular portion 24 are engaged and locked into the groove 42a of the outer conductor 42, as illustrated in FIG. 8A. On the other hand, a region 25d where the projections are not formed has no portions engaged in the groove 42a, as illustrated in FIG. 8B.

In this preferred embodiment, as illustrated in FIG. 7B, the first locking projection 25a acts as a fulcrum C, and each of the second and third locking projections 25b and 25c each having a predetermined beam length from the fulcrum C acts as a point C' of effort. According to the load theory of a cantilevered beam, a load acting on the point C' of effort is inversely proportional to the third power of the beam length. Therefore, loads acting on the projections 25a, 25b and 25c are significantly smaller than those when the second and third locking projections 25b and 25c are formed at positions within 90° with respect to the first locking projection 25a. As a result, the projections 25a, 25b and 25c are prevented from displacing beyond the spring elastic limit displacement when the coaxial connector is attached and detached. Thus, the coaxial connector can be attached and detached a great number of times without problems.

Note that the locking projections 25a, 25b and 25c are preferably formed, as described above, integrally with the tubular portion 24 in the state slightly projecting inward of the tubular portion 24 rather than the state separated from the tubular portion 24 through a slit or a groove.

FIGS. 9 and 10 illustrate a modification of the tubular portion 24 of the housing 21. In the modification of the tubular portion 24, vertical slits 25e are formed in a lower portion of the tubular portion 24 to extend from its lower end between the first and second locking projections 25a and 25b and between the first and third locking projections 25a and 25c, respectively. Further, horizontal slits 25f are formed in the

tubular portion 24 to extend from opposite edges of the gap 29 perpendicularly or substantially perpendicularly to the press-fitting direction A.

By forming the vertical slits 25e and the horizontal slits 25f, the spring elasticity of the tubular portion 24 is increased. Therefore, the coaxial connector 1 is more easily attached to and detached from the receptacle 41, and the life of the coaxial connector 1 is further prolonged. As an alternative, only one of the vertical slits 25e or the horizontal slits 25f may be formed.

In the coaxial connector described above, the first locking projection is preferably located at a position on the circumference of the tubular portion diametrically opposite to the gap, and the second and third locking projections are preferably located at positions that are spaced away from the first locking projection by about 90° or more in the circumferential direction. When the tubular portion is locked to the outer conductor of the receptacle, the first locking projection acts as a fulcrum and each of the second and third locking projections having a predetermined beam length with respect to the fulcrum acts as a point of effort instead of the entire circumference of the tubular portion being press-fitted into the groove of the receptacle. Such an arrangement eliminates the necessity of applying such a strong load. As a result, the locking projections of the tubular portion are prevented from displacing beyond the spring elastic limit displacement when the coaxial connector is attached and detached. Further, the coaxial connector can be attached and detached a great number of times without problems.

In the coaxial connector according to various preferred embodiments of the present invention, the coaxial cable may be connected to the housing and the socket perpendicularly or substantially perpendicularly to the press-fitting direction (i.e., the right angle type), or may be connected parallel or substantially parallel to the press-fitting direction (i.e., the straight type).

The first, second and third locking projections may be each formed in the state of the tubular portion being projected inward. A vertical slit may be formed in a lower portion of the tubular portion to extend from its lower end between the first locking projection and each of the second and third locking projections. Further, a horizontal slit may be formed in the tubular portion to extend from the gap perpendicularly or substantially perpendicularly to the press-fitting direction. The presence of the vertical slit and the horizontal slit increases the spring elasticity of the tubular portion. As a result, the coaxial connector is more easily attached to and detached from the receptacle, and the life of the coaxial connector is further prolonged.

The coaxial connector according to the present invention is not limited to the above-described preferred embodiments and can be variously modified within the scope of the present invention.

For example, while the opposite edges of the gap formed in the tubular portion of the housing are preferably positioned close to each other in the above-described preferred embodiments, those edges may be positioned away from each other by a predetermined width.

As described above, the present invention is useful when practiced as a coaxial connector for connecting a coaxial cable to a receptacle. Particularly, the present invention is advantageous in that the coaxial connector can be attached to and detached from the receptacle plural times with a smaller load and has a longer life without increasing the height of the coaxial connector.

While preferred embodiments of the present invention have been described above, it is to be understood that varia-

tions and modifications will be apparent to those skilled in the art without departing the scope and spirit of the present invention. The scope of the present invention, therefore, is to be determined solely by the following claims.

What is claimed is:

1. A coaxial connector for connecting a coaxial cable having a central conductor and an outer conductor to a receptacle having a central conductor and an outer conductor, the coaxial connector comprising:

a housing connected to the outer conductor of the coaxial cable and having a tubular portion arranged to be press-fitted and locked into a groove provided in the outer conductor of the receptacle;

a socket connected to the central conductor of the coaxial cable and arranged to be connected to the central conductor of the receptacle; and

an insulating bushing mounted into the tubular portion of the housing and holding the socket; wherein the tubular portion has a substantially C-shape extending

perpendicularly or substantially perpendicularly to a direction in which the tubular portion is press-fitted to the outer conductor of the receptacle, and has a gap extending parallel or substantially parallel to the press-fitting direction; and

the tubular portion has three first, second and third locking projections to be press-fitted and locked into the groove provided in the outer conductor of the receptacle to extend perpendicularly or substantially perpendicularly to the press-fitting direction, the first locking projection

5

10

15

20

25

being located at a position on a circumference of the tubular portion diametrically opposite to the gap, the second locking projection and the third locking projection being located at positions spaced away from the first locking projection by about 90° or more in a circumferential direction, and a circumferential length of each of the first, second and third locking projections is smaller than a circumferential length of an interval between the first locking projection and the second or third locking projection.

2. The coaxial connector according to claim 1, wherein the coaxial cable is connected to the housing and the socket perpendicularly or substantially perpendicularly to the direction in which the tubular portion is press-fitted to the outer conductor of the receptacle.

3. The coaxial connector according to claim 1, wherein the first, second and third locking projections are each arranged in a state of the tubular portion being projected inward.

4. The coaxial connector according to claim 1, wherein a vertical slit is arranged in a lower portion of the tubular portion to extend from a lower end thereof between the first locking projection and each of the second and third locking projections.

5. The coaxial connector according to claim 1, wherein a horizontal slit is arranged in the tubular portion to extend from the gap perpendicularly or substantially perpendicularly to the press-fitting direction.
